UNITED STATES PATENT OFFICE.

NATHANIEL H. SHAW, OF SOMERVILLE, MASSACHUSETTS, ASSIGNOR, BY DIRECT AND MESNE ASSIGNMENTS, TO THE AMERICAN AUTOMATIC GAS-LIGHTING COMPANY, OF PORTLAND, MAINE.

APPARATUS FOR AUTOMATICALLY LIGHTING AND EXTINGUISHING GAS-BURNERS.

SPECIFICATION forming part of Letters Patent No. 393,271, dated November 20, 1888.

Application filed October 8, 1887. Serial No. 251,853. (No model.)

To all whom it may concern:

Be it known that I, NATHANIEL H. SHAW, of Somerville, in the county of Middlesex, State of Massachusetts, have invented a certain new and useful Improvement in Apparatus for Automatically Lighting and Extinguishing Gas-Burners, of which the following is a description sufficiently full, clear, and exact to enable any person skilled in the art or science to which said invention appertains to make and use the same, reference being had to the accompanying drawings, forming part of this specification, in which—

Figure 1 is a front elevation of my improved apparatus represented as in use; Fig. 2, a like view, one of the dials and the face-plate being removed to show the working parts; Fig. 3, a side elevation, the gas-pipe being shown as broken off; and Fig. 4, a plan view showing certain details of construction.

Like letters of reference indicate corresponding parts in the different figures of the drawings.

My invention relates more especially to means for automatically lighting and extinguishing the gas in street-lamps; and it consists in a novel construction and arrangement of parts, as hereinafter more fully set forth and claimed, the object being to produce a more effective and otherwise desirable device of this character than is now in ordinary use.

The nature and operation of the improvement will be readily understood by all conversant with such matters from the following explanation.

In the drawings, A represents the clock, B the dynamo or other spark-forming device, and C the gas-burner.

The clock A furnishes the motive power for certain part of the mechanism hereinafter referred to; but as it is of the form and construction of ordinary eight day clocks it is not deemed essential to more particularly describe it. The clock and connecting mechanism are attached to a supporting-plate, D, by means of which the apparatus may be secured to a lamp-post or in any other desired position. A bed-plate, E, (see Fig. 2,) is secured to the plate D, and a face-plate, G, supported on the

pillars 90, (see Fig. 1,) covers the mechanism, 50 the shafts of which are journaled in the plates G E.

The clock A is preferably disposed at the lower left-hand corner of the plate D, as shown in Fig. 2. A gear, b, is disposed on a shaft, 55 d, journaled in the plates G E, said gear intermeshing with the barrel-wheel a of the clock, and being provided with such a number of teeth that said barrel-wheel will cause it to make one complete revolution in twenty-four 60 hours. Journaled loosely on the shaft f, disposed directly above the gear b, (see Fig. 3,) there is a gear, g, which intermeshes with the gear b, and is provided with a corresponding number of teeth. A friction-plate, h, is se- 65 cured on the shaft f, the ends of said plate pressing against the outer face of the gear g and forcing it against the shoulder 95, so that when said gear is revolved the friction-plate will revolve said shaft.

The plate G is provided with a dial, H, (see Fig. 1,) divided into twenty-four equal parts and numbered consecutively from 1 to 24, the indicating-hands i being disposed on the outer end of the shaft f, which serves as an arbor 75 for said hands.

Between the gear g and plate E on the shaft f are loosely journaled two worm-gears, k l, (see Fig. 3,) said gears being respectively provided with outwardly-projecting studs m p. 80 The gears k l are separated by a bracket, q, which is rigidly secured by its inner end to the shaft f. Projecting laterally from the outer end of said bracket are arms v, and journaled in parallelism with each other in said arms 85 are two horizontally-arranged worms, r t, (see Fig. 4,) which respectively engage the gears k l. The worms r t are connected at one end by pinions w, and the worm t provided at the end opposite said pinions with a sprocket- 90 wheel, x.

A horizontally-arranged bar, y, is fitted to slide in ways formed in the plates G E D, said bar being provided with two inwardly-projecting pins, 10 and 11, of such length that 95 when the bracket q is revolved by the shaft f one of the pins z on the sprocket-wheel x will engage one of the pins, 10 or 11, as the case

may be, on said bar, and thereby cause the worms r t to revolve. The worms r t , connected by the pinions w w and provided with the sprocket-wheel x , in connection with the bracket q , shaft f , worm-gears k l , provided with the studs m p , friction-gear g , and bar y , provided with the pins 10 and 11, constitute a regulating device to compensate for the variation in the length of the days and nights at different seasons of the year, the operation of which is hereinafter described.

The gas-burner C is provided with an ordinary stop-cock or ball-valve, 75, which is operated by a horizontally-arranged shaft, 12, journaled in the plates G E , and having its outer end rigidly secured in a hub, 76, cast on the barrel-wheel J . An actuating device resembling the ordinary striking mechanism of a clock inverted is disposed above the regulating mechanism between the plates G E . The actuating device consists, essentially, of a barrel-wheel, J , gears 96, 21, and 50, and the governor or fan wheel 97. The barrel is mounted on a shaft, 12, and arbor 15, the arbor being disconnected from the shaft and having its inner end journaled in a step within the barrel, to enable it to be turned independently of the shaft in winding up a spring, (not shown,) which is disposed within the barrel in the usual manner of clock-springs. The barrel-wheel (see Fig. 3) intermeshes with a pinion, 98, on the shaft 99 of the gear 96, the gear 96 intermeshes with a pinion, 102, on the shaft 103 of the gear 21, the gear 21 intermeshes with a pinion, 104, on the shaft 105 of the gear 50, and the gear 50 with a pinion, 106, on the shaft 107 of the fan-wheel 97. The periphery of the barrel-wheel J is provided with gear-teeth in the ordinary manner, and also with four indentations, 16, disposed equidistant from each other, as shown in Fig. 2, for receiving the end of the drop-wire 17.

The dynamo B is of the form and construction of ordinary friction-dYNAMOS as found in many electric lamp-lighters, and is actuated by means of a pinion, 19, which intermeshes with one of the gear-wheels, 21, in the mechanism last referred to. Any other well-known spark-forming device may be used, if preferred, provided it be so arranged and connected as to operate successfully with the other portions of my device. Two pendulous hook-shaped wires, 28 and 29, are pivoted by means of a rocking shaft, 25, journaled in the plates G and E , said wires being connected by a brace or cross-bar, 26, (see Fig. 3,) and so arranged that the stud m on the worm-gear k will engage the hook 30, Fig. 2, of the wire 28, and the stud p on the worm-gear l engage the hook 78 on the wire 29, as said gears are revolved. The drop-wires 17 are secured to a rocking shaft, 35, said shaft being provided with a spring to keep the free end of said wire in engagement with the periphery of the barrel-wheel J . Secured to the shaft 35 there is also an upwardly-projecting curved locking-wire, 37, (see Fig. 3,) provided with a laterally and

outwardly projecting arm, 38, which rests against the periphery of a locking-disk, 40, mounted on the shaft 103 of the gear 21 and rigidly secured thereto. The disk 40 is in the shape of a segment of a circle, and its straight edge or chord is provided centrally with a recess, 42, for receiving the arm 38 of the locking-wire 37 when the arm 35 of the drop-wire 17 falls into one of the recesses 16 in the wheel J . To the shaft 25 is secured an upwardly-projecting curved releasing-wire, 45, (see Figs. 2 and 3,) having a laterally and outwardly projecting arm, 46, which rests against the drop-wire 17, and is designed to remove said wire from contact with the barrel-wheel J , as hereinafter described. A laterally-projecting wire, 47, is also secured to the shaft 25, said wire being adapted to engage a stud, 48, on the gear 50 of the actuating device. A counter-balance, 51, is also attached to the shaft 25, to keep the hook-shaped wires 28 and 29 in position to be engaged by the studs m p on the wheels k l ; but said counter-balance may be omitted, if desired.

The rocking shaft 25, wires 17, 37, and 47, disk 40, and stud 48 constitute a locking device for the actuating mechanism, and the wires 28 and 29, rocking shaft 25, and wire 45, in combination with the studs m p , constitute a let-off mechanism for releasing the locking device.

The operation of the apparatus is as follows: The clock A and also the spring within the barrel-wheel J are first wound up in the usual manner. It having been previously determined at what hour in the evening it is desired to light the gas, (which will depend upon the length of the day or season of the year,) the hands i on the dial H are set to correspond with the time indicated by the hands of the clock A . This causes the shaft f to be revolved, carrying with it the bracket q , and the worm-gears k l to be so set or adjusted that the stud m on the gear k will be in position to engage the hook 30 of the wire 28 at the time fixed upon for lighting the gas. If the days and nights are practically of the same length—as, for instance, in the month of December—the stud p on the gear l will then stand diametrically opposite the stud m on the gear k , or nearly so, as shown in Fig. 2, so that it will engage the hook 78 on the wire 29 twelve hours after the stud m has engaged the wire 28, it being understood that the wheels b g make but one revolution in twenty-four hours, as stated. The apparatus having been adjusted as described, if, for example, it is desired to light the gas at 6.45 o'clock post meridian, when the clock A has reached this hour, as shown in Fig. 1, its barrel-wheel a will have turned the gears b g in the direction of their arrows (see Fig. 2) and revolve the shaft f by means of the friction-plate h in the direction of the arrow 61. The bracket q , being secured to the shaft f , revolves with it, and as the worms r t are supported on said bracket, connected with each other, and engaged with

gears l l , they will cause said gears to revolve with them from left to right. When the stud m on the wheel k strikes the hook 30 of the wire 28, said wire, being secured to the shaft 5 25, is moved outward and turns said shaft from left to right, thereby forcing the arm 46 of the wire 45 against the drop-wire 17, disengaging the arm 85 of said wire from the barrel-wheel J , and at the same time removing the arm 38 of the locking-wire 37 from the slot 42 of the locking-disk 40. As soon as the locking-disk 40 is released the barrel J immediately begins to revolve in the direction of its arrow, (sec. Fig. 2,) thereby setting in motion the train of gears. The shaft 12 is thereby turned a quarter-revolution and the valve 75 opened, thus permitting the gas to pass from the pipe 80 to the burner C and become ignited by a spark from the dynamo, 10 15 20 which has been meanwhile rotated by the revolution of pinion 19, in a manner that will be readily obvious without a more explicit description.

It will be understood that the arm 85 on the drop-wire 17 falls into the shallow spaces between the teeth of the wheel J , in the usual manner, and that when said wheel has revolved one-quarter of its circumference said arm will drop into one of the deep recesses 16, 25 30 35 and thereby permit the locking-wire 37 to lock the disk 40 and stop the mechanism actuated by the wheel J . When, however, the stud m engages the hook 30 on wire 28 and withdraws the arm 85 of the wire 17 from the recess 16 in the wheel J and said wheel commences to turn and has advanced the distance of one tooth, the wire 47 on the shaft 25 engages the pin 48 on the wheel 50, thus preventing said wheel from revolving further 40 45 until said stud passes the hook 30 of the wire 28. It will thus be seen that the barrel-wheel J is tripped ready to revolve, but held from such revolution by the arm 47 engaging pin 48. When the stud m passes the end of hook 30, the arm 47 is released from engagement with pin 48, and the uninterrupted movement of barrel-wheel J , and with it the train of gears actuated thereby, commences.

In the morning, when the time arrives to 50 55 60 65 shut off the gas, the stud p on the wheel l , which during the night has made a half-revolution and engaged the hook 78 on the wire 29, at the proper moment passes the end of said hook, thereby again releasing the barrel-wheel J and allowing it to be revolved another quarter of its circumference in substantially the same manner as already described, the valve 75 being closed by this quarter-revolution by means of the shaft 12, which is revolved jointly with said barrel. The spark created by this quarter-revolution obviously has no result, as the gas is shut off.

The operation of the regulating mechanism referred to is as follows: If the days are increasing in length, the bar y is adjusted so that its pin 10 will engage a pin z on the left-hand side of the wheel x on the worm t , thereby causing

the wheel x to be revolved from left to right the distance between two of its pins z at each revolution of the shaft f , which occurs once in twenty-four hours, as described. The worm t being thus rotated produces a corresponding rotation of the gear l from left to right a proportionate distance, and at the same time turns the worm r by means of the pinions w , thereby revolving the gear k an equal distance from right to left. This gradually brings the studs m p nearer to each other as they move in the direction shown by the arrows 65 in Fig. 2, the interval between the time the burner is lighted by means of the stud m and extinguished by means of the stud p and their connecting mechanism, as described, growing proportionately shorter as the studs approach each other. The gears l l and worms r t are so constructed that the distance said gears will be revolved at each revolution of the worms will correspond with the variation in the length of the days, thereby compensating for said variation and regulating the lighting and extinguishing of the gas in accordance therewith.

It will be understood that at the expiration of six months, or when the days begin to grow shorter, it will be necessary to adjust the bar y so that its pin 11 will engage the pins z on the right-hand side of the wheel x and cause the worms to operate in an opposite direction, thereby gradually increasing the distance between the studs m p , and hence increasing the time between the lighting and extinguishing of the gas proportionately.

The plates G E are detachably connected by pillars 90 after the manner of connecting the face and bed plates in ordinary clock-movements.

The dynamo B is disposed on a bracket, 120, which projects horizontally from the supporting-plate D , but may be sustained in any suitable manner.

I do not confine myself to the use of an electric dynamo for generating a spark or producing fire to ignite the gas, as that portion of the apparatus which is disposed between the plates G E , in connection with the clock A , is adapted to operate mechanism for producing a spark or fire by percussion, striking a match, &c., as well as by electric action.

It will be understood that the clock A and barrel-wheel J are to be wound up as often as required to run the mechanism continuously.

Having thus explained my invention, what I claim is—

1. The regulating mechanism herein described, comprising the shaft f , journaled in plates G E , bracket g , rigidly secured to said shaft, worms r t , journaled in said bracket and provided with intermeshing gears w , sprocket-wheel x upon the shaft of one of said worms, gears k l , engaging said worms, the gears being journaled loosely upon said shaft f and provided with studs m and p , power-gear g on shaft f , means for revolving it once in twenty-four hours, and pins 10 and 11, adapted to en-

gage said sprocket-wheel on either side for the purpose set forth, in combination with the wires 28 and 29, adapted to engage said studs, shaft 25, to which said wires are attached, and 5 tripping wires 45 and 47, carried by said shaft 25, as and for the purpose described.

2. The regulating mechanism herein described, comprising the shaft *f*, journaled in plates *G E*, bracket *q*, rigidly secured to said shaft, worms *r t*, journaled in said bracket and provided with intermeshing gears *w*, sprocket-wheel *x* upon the shaft of one of said worms, gears *k l*, engaging said worms, the gears being journaled loosely upon said shaft *f* and provided with studs *m* and *p*, power-gear *g* on shaft *f*, means for revolving it once in twenty-four hours, dial *H*, hands *i*, carried by said shaft, and the adjustable bar *y*, provided with pins 10 and 11, adapted to engage said sprocket-wheel for the purpose set forth, in combination with the wires 28 and 29, adapted to engage said studs, shaft 25, to which said wires are attached, and tripping-wires 45 and 47, carried by said shaft 25, as and for the purpose described.

3. The regulating mechanism herein described, comprising the shaft *f*, journaled in plates *G E*, bracket *q*, rigidly secured to said shaft, worms *r t*, journaled in said bracket and provided with intermeshing gears *u*, sprocket-wheel *x* upon the shaft of one of said worms, gears *k l*, engaging said worms, the gears being journaled loosely upon said shaft *f* and provided with studs *m* and *p*, power-gear *g*, also journaled loosely on said shaft and resting against a shoulder, 95, a spring-plate, *h*, on said shaft next the gear *g*, a pin in the shaft for holding said plate and gear in frictional contact, means for revolving said gear and with it the shaft once in twenty-four hours, dial *H*, hands *i*, carried by said shaft, and the adjustable bar *y*, provided with pins 10 and 11, adapted to engage said sprocket-wheel for the purpose set forth, in combination with the wires 28 and 29, adapted to engage said studs, shaft 25, to which said wires are attached, and tripping-wires 45 and 47, carried by said shaft 25, as and for the purpose described.

4. The gas-burner C, valve 75 therein, and
50 rod 12, connected to said valve, in combination
with the spring-actuated barrel-wheel J, hav-
ing deep recesses 16 at quartering points in
its circumference, the coupling 76, connecting
rod 12 with the axis of said barrel-wheel, a
55 train of gears driven by said barrel-wheel, a
disk, 40, having recess 42 upon the shaft of
one of said gears, a shaft, 35, carrying drop-
wire 17, for engaging said deep recesses 16 in
the barrel-wheel, and also carrying locking-
60 wire 37, for simultaneously engaging the re-
cess in said disk, a rocking shaft, 25, carrying
releasing-wire 45, for tripping the drop-wire
17, and also carrying pendulous wires 28 and
29, and wheels k, l, revolving once in twenty-four
65 hours and carrying studs m p, located, respect-
ively, thereon and at approximately-opposite
points, said studs m and p striking said wires

alternately to trip the drop-wire 17 and permit a quarter-revolution of the barrel-wheel J, all substantially as described.

5. The gas-burner C, valve 75 therein, and rod 12, connected to said valve, in combination with the spring-actuated barrel-wheel J, having deep recesses 16 at quartering points in its circumference, the coupling 76, connecting rod 75 12 with the axis of said barrel-wheel, a train of gears driven by said barrel-wheel, a disk, 40, having recess 42 upon the shaft of one of said gears, a shaft, 35, carrying drop-wire 17, for engaging said deep recesses 16 in the barrel-wheel, and also carrying locking-wire 37, for simultaneously engaging the recess in said disk, a rocking shaft, 25, carrying releasing-wire 45, for tripping the drop-wire 17, and also carrying pendulous wires 28 and 29, and a 85 regulating mechanism, substantially as described, adapted to trip said wires 28 and 29 alternately for permitting quarter-revolutions of the barrel-wheel J at proper intervals, substantially as specified. 90

6. The gas-burner C, valve 75 therein, and rod 12, connected to said valve, in combination with the spring-actuated barrel-wheel J, having deep recesses 16 at quartering points in its circumference, the coupling 76, connecting rod 12 with the axis of said barrel-wheel, a train of gears driven by said barrel-wheel, a pin, 48, in one of said gears, a disk, 40, having recess 42 upon the shaft of another of said gears, a shaft, 35, carrying drop-wire 17, for engaging said deep recesses 16 in the barrel-wheel, and also carrying locking-wire 37, for simultaneously engaging the recess in said disk, a rocking shaft, 25, carrying releasing-wire 45, for tripping the drop-wire 17, also carrying stop-wire 47, for abutting against said pin 48 to check the movement of the train of gears after it has been started by the tripping-wire, and also carrying pendulous wires 28 and 29, having hooks 30 78 at their ends, and wheels k l, revolving once in twenty-four hours and carrying studs m p, located, respectively, thereon and at approximately opposite points, said studs m and p striking said hooks alternately to trip the drop-wire 17, and later disengaging said hooks by passing their ends to release stop-wire 47 and permit a quarter-revolution of the barrel-wheel J, all substantially as described. 95 105 110 115

7. The gas-burner C, valve 75 therein, and rod 12, connected to said valve, in combination with the spring-actuated barrel-wheel J, having deep recesses 16 at quartering points in its circumference, the coupling 76, connecting rod 12 with the axis of said barrel-wheel, a train of gears driven by said barrel-wheel, a disk, 40, having recesses 42 upon the shaft of one of said gears, a spark-forming device, B, mounted on a shaft carrying a pinion engaging one of said gears and adapted to be operated thereby when the latter is revolved, a shaft, 35, carrying drop-wire 17, for engaging said deep recesses 16 in the barrel-wheel, and also carrying locking-wire 37, for simultaneous operation of the coupling 76 and the drop-wire 17.

ously engaging the recess in said disk, a rocking shaft, 25, carrying releasing-wire 45, for tripping the drop-wire 17, and also carrying pendulous wires 28 and 29, and wheels *k l*, revolving once in twenty-four hours and carrying studs *m p*, located, respectively, thereon and at approximately-opposite points, said studs *m* and *p* striking said wires alternately to trip the drop-wire 17 and permit a quarter-revolution of the barrel-wheel *J*, all substantially as described.

8. The gas-burner *C*, valve 75 therein, and rod 12, connected to said valve, in combination with the spring-actuated barrel-wheel *J*, having deep recesses 16 at quartering points in its circumference, the coupling 76, connecting rod 12 with the axis of said barrel-wheel, a train of gears driven by said barrel-wheel, a spark-forming device, *B*, mounted upon a shaft carrying a pinion engaging one of said gears and adapted to be operated thereby when the latter is revolved, a pin, 48, in one of said gears, a disk, 40, having recess 42 upon the shaft of another of said gears, a shaft, 35, carrying drop-wire 17, for engaging said deep recesses 16 in the barrel-wheel, and also carrying locking-wire 37, for simultaneously engaging the recess in said disk, a rocking shaft, 25, carrying releasing-wire 45, for tripping the drop-wire 17, also carrying stop-wire 47, for abutting against said pin 48 to check the movement of the train of gears after it has been started by the tripping-wire, and also carrying pendulous wires 28 and 29, having hooks 30 78 at their ends, and wheels *k l*, revolving once in twenty-four hours and carrying studs *m p*, located, respectively, thereon and at approximately-opposite points, said studs *m* and *p* striking said hooks alternately to trip the drop-wire 17, and later disengaging said hooks by passing their ends to release stop-wire 47 and permit a quarter-revolution of the barrel-wheel *J*, all substantially as described.

45 9. The gas-burner *C*, valve 75 therein, and rod 12, connected to said valve, in combination with a spring-actuated barrel-wheel, *J*, having deep recesses 16 at quartering points in its circumference, the coupling 76, connecting rod 12 with the axis of said barrel-wheel, a train of gears driven by said barrel-wheel, a pin, 48, in one of said gears, a disk, 40, having recess 42 upon the shaft of another of said gears, a shaft, 35, carrying drop-wire 17, for engaging said deep recesses 16 in the barrel-wheel, and also carrying locking-wire 37, for simultaneously engaging the recess in said disk, a rocking shaft, 25, carrying releasing-wire 45, for tripping the drop-wire 17, also carrying stop-wire 47, for abutting against said pin 48 to check the movement of the train of gears after it has been started by the tripping-wire, and also carrying pendulous wires 28 and 29, having hooks 30 78 at their ends, the

shaft *f*, journaled in plates *G E*, bracket *q*, rigidly secured to said shaft, worms *r t*, journaled in said bracket and provided with intermeshing gears *w*, sprocket-wheel *x* upon the shaft of one of said worms, gears *k l*, engaging said worms, the gears being journaled loosely upon said shaft *f* and provided with studs *m* and *p*, power-gear *g* on shaft *f*, means for revolving it once in twenty-four hours, dial *H*, hands *i*, carried by said shaft, and the adjustable bar *y*, provided with pins 10 and 11, adapted to engage said sprocket-wheel for the purpose set forth, said studs *m* and *p* striking said hooks alternately to trip the drop-wire 17, and later disengaging said hooks by passing their ends to release stop-wire 47 and permit a quarter-revolution of the barrel-wheel *J*, all substantially as described.

10. The gas-burner *C*, valve 75 therein, and rod 12, connected to said valve, in combination with the spring-actuated barrel-wheel *J*, having deep recesses 16 at quartering points in its circumference, the coupling 76, connecting rod 12 with the axis of said barrel-wheel, a train of gears driven by said barrel-wheel, a spark-forming device, *B*, mounted upon a shaft carrying a pinion engaging one of said gears and adapted to be operated thereby when the latter is revolved, a pin, 48, in one of said gears, a disk, 40, having recess 42 upon the shaft of another of said gears, a shaft, 35, carrying drop-wire 17, for engaging said deep recesses 16 in the barrel-wheel, and also carrying locking-wire 37, for simultaneously engaging the recess in said disk, a rocking shaft, 25, carrying releasing-wire 45, for tripping the drop-wire 17, also carrying stop-wire 47, for abutting against said pin 48 to check the movement of the train of gears after it has been started by the tripping-wire, and also carrying pendulous wires 28 and 29, having hooks 30 78 at their ends, the shaft *f*, journaled in plates *G E*, bracket *q*, rigidly secured to said shaft, worms *r t*, journaled in said bracket and provided with intermeshing gears *w*, sprocket-wheel *x* upon the shaft of one of said worms, gears *k l*, engaging said worms, the gears being journaled loosely upon said shaft *f* and provided with studs *m* and *p*, power-gear *g* on shaft *f*, means for revolving it once in twenty-four hours, dial *H*, hands *i*, carried by said shaft, and the adjustable bar *y*, provided with pins 10 and 11, adapted to engage said sprocket-wheel for the purpose set forth, said studs *m* and *p* striking said hooks alternately to trip the drop-wire 17, and later disengaging said hooks by passing their ends to release stop-wire 47 and permit a quarter-revolution of the barrel-wheel *J*, all substantially as described.
